Application March 5, 1935, Serial No. 55,747

Term of patent 3½ years

To all whom it may concern:

Be it known that I, Samuel Libou, a citizen of the United States of America, residing at New York, in the county of New York and State of New York, have invented a new, original, and ornamental Design for a Curtain, of which the following is a specification, reference being had to the accompanying drawing, forming a part hereof.

Figure 1 is a plan view showing the quarter sections of the curtain, the broken away portions being a design repeat of the fabric design shown in detail in Figure 2.

Figure 2 is an enlarged sectional view of the body of the curtain, taken in the center thereof, of the curtain shown in Figure 1.

The characteristic feature of the design resides in the contrasting color areas of the curtain resulting in a plaid design.

I claim:

The ornamental design for a curtain as shown and described.

SAMUEL LIBOU.
